STOP CYLINDER VERTICAL RECIPROCAT-
ING FLAT BED PRESS

Paul F. Cox, Chicago, Ill.

Application December 27, 1938, Serial No. 247,932

21 Claims. (Cl. 101—264)

This invention is an improvement in bed and cylinder printing presses, and its principal object is to provide an efficient web perfecting press adapted to print a web by means of flat forms of type, or other flat printing surfaces, mounted upon vertically movable beds and coacting with impression cylinders that preferably rotate during the printing strokes of the beds and are stopped during the return strokes of the beds. 5

A further object is to provide a press which will produce good clean-cut impressions on hard-finished or book paper, and especially adapted for small printing offices which need a roll-feed web press that will be less expensive and produce a 10 better grade of work than can be printed on the flat bed web presses now on the market.

A further object of the invention is to produce a web printing perfecting press in which the beds are mounted in a central section; the feed roll, 15 first impression cylinder and inking mechanism for the first bed are mounted in an end section; and the second impression cylinder, inking mechanism for the second bed, and the delivery mechanism, and if desired re-winding mechanism, are mounted in another end section; this construction 20 enables the mechanisms of the press to be completely assembled in the respective sections at the factory and shipped complete to the user; and set up in situ and secured together by ordinary mechanics, without the necessity of having an expert press mechanic assemble the parts in the buyer's pressroom; this effecting a great 25 saving to the purchaser. Further my press requires no pit, which effects a further saving to the purchaser.

In the example shown in the accompanying drawings my press includes two vertically movable beds which are reciprocated by crank wheels and pitmans, such beds being counter-balanced to 30 relieve the crank pins of weight and enhance the speed of the press. The impression cylinders coact with the beds on one stroke thereof, and are stopped on the return stroke with the gaps in the cylinders (required for the blanket reel rods) adjacent the beds; in such position the gaps permit the beds to return without contacting the web, and thus obviates the necessity for employment of eccentrics or other mechanism to throw off impressions. The beds face oppositely 35 and outwardly, and the cylinders are disposed at the outer sides of the beds, thus enabling the ink mechanisms to be arranged beneath the cylinders and fully accessible from the ends of the press.

Other minor objects and novel features of the 40 invention will be hereinafter referred to in the detailed description of the press illustrated in the accompanying drawings, which show one practical embodiment of my invention.

In said drawings—

Fig. 1 is a side elevation of the press.

Fig. 2 is a view of the delivery end of press with the cutting cylinders removed.

Fig. 3 is a horizontal section on line 3—3, Fig. 1.

Fig. 4 is a diagrammatic vertical longitudinal 5 sectional view of the press, illustrating the web leads.

Fig. 5 is a similar view showing the lead of webs when assembling re-wound web with main web.

Fig. 6 is an enlarged horizontal detail section 10 on line 6—6, Fig. 7.

Fig. 7 is an enlarged detail view of the cylinder clutching mechanism, showing gear locked to cylinder.

Fig. 8 is a view similar to Fig. 7, showing gear 15 freed from cylinder.

Fig. 9 is a detail view of the drive mechanism.

Fig. 10 is a side elevation of the press, showing the sections A, B, C spaced apart.

The press shown comprises two vertically disposed oppositely outwardly facing type beds 1 and 2 rigidly connected at their outer sides by cross bars 3 which hold the beds rigidly together and in sliding engagement with vertically disposed guides 3a on the side frames of the central section B of the press (see Figs. 1 and 3). The beds may be reciprocated vertically by means of pitmen 4 pivotally connected to the outer ends of a shaft 4a (that extends between the beds and through the lower bars 3), and to crank pins on 20 wheels 4b fixed on a transverse shaft 4c journaled in bearings in the opposite side frames of the central section A of the press and disposed vertically above and parallel with shaft 4a. (See Fig. 1.)

In the construction shown one of the wheels 4b is provided with gear teeth that mesh with a pinion 4d on a stub shaft 4e journaled in the adjacent side frame of section B and in a bracket 4f attached thereto (see Figs. 2 and 9). On stub shaft 4e is a pulley 4g which may be driven by a belt 4h from any suitable motor or driver (not shown). The shaft 4c constitutes the main drive shaft of the press, and from it motion is imparted to the other mechanisms of the press.

To facilitate the operation of the beds without shock or jar, they are counterbalanced. As shown an oppositely movable weight 1x is connected to bed 1 by chains 1y running over pulleys 1z mounted on a shaft 1w journaled in the frames 50 of the central section B of the press above shaft 4c. (See Fig. 1.) Similarly bed 2 is counterbalanced by a weight 2x connected to the bed by chains 2y running over pulleys 2z on a shaft 2w mounted on the central section B of the press. 55 The counterbalancing weights may be guided by and between the beds, as indicated in Figs. 1 and 3.

Cooperating with bed 1 is an impression cylinder 6 which is journaled in bearings in the in- 60

feed section A of the press, and is disposed opposite the upper end of bed 1 when said bed is in its lowest position. The cylinder 6 has bearers 6a engaging bearers on the bed (Fig. 3) and on one of the cylinder journals is a gear 6b that meshes with a rack 1b on bed 1.

Suitable clutches are provided by which the gear 6b is automatically locked to and disengaged from cylinder 6 at such times that the cylinder 10 will be rotated at a peripheral speed in unison with the travel of the bed during the printing (or down) stroke of the bed, and will be stopped during the non-printing (or up) stroke of the bed.

15 In the construction shown (see Figs. 6 to 8) the gear 6b is loose on the shaft of cylinder 6 and has a transverse slot in its outer face for engagement with a lock bar 6c which is attached to the inner end of a rod 6d that is normally 20 impelled outwardly by an expansion spring 6e guided in a bore in the shaft of cylinder 6; said shaft also having a transverse slot to permit lateral movement of the bar 6c into and out of the slot in gear 6b. A sleeve 6f is loosely mounted 25 on the cylinder shaft, between gear 6b and the frame, and is locked against rotation by a finger 6g attached to the frame. In the inner end of the sleeve adjacent gear 6b is a slot into which lock bar 6c enters when it is disengaged from gear 6b. On the inner end of sleeve 6f is loosely mounted a cam 6i having a cam surface 6j adapted to engage bar 6c, and said cam is provided with a peripheral stud 6k adapted to be engaged by a pin 6m on gear 6b. On sleeve 6f is slidably 35 mounted a plate 6o which is provided with pins 6p engaging holes in the adjacent side frame, and expansion springs 6q on said pins normally press plate 6o toward and against cam 6i.

Fig. 7 shows the parts in positions assumed 40 when lock bar 6c has been pushed into the slot in gear 6b by cam 6j. This occurs as bed 1 reaches its uppermost position, at which time the grooves in gear 6b and sleeve 6f coincide. Then while the bed 1 moves down the printing 45 cylinder 6 makes one revolution, stops with its gap opposite the bed, and as the bed reaches its lowermost position the lock bar is disengaged from gear 6b, and withdrawn into sleeve 6f, so that on the upstroke of the bed the cylinder is 50 stationary. As the bed rises the gear 6b rotates in a reverse direction, but cylinder 6 remains stationary. The lock bar is prevented from disengaging gear 6b at a half revolution of the cylinder by the cam 6j, which remains in the 55 position shown in Fig. 7 until just before the position shown in Fig. 8 is reached. As the bed rises gear 6b rotates in opposite direction until pin 6m (Fig. 7) engages opposite side of lug 6k, Fig. 8. As gear 6b nears end of rotation in reverse direction (as bed rises) pin 6m eventually contacts lug 6k from the opposite side and moves cam 6i to the right (Fig. 8).

Fig. 8 shows the position of parts just after the lock bar has been disengaged from gear 6b, 65 and engaged with the sleeve 6f. The pin 6m (moving in reverse direction) has engaged lug 6k and moved cam 6j to allow lock bar 6c to be drawn into the groove in the sleeve by the action of spring 6e.

70 As cam 6i is moved to the right (Fig. 8) it is forced outwardly on sleeve 6f moving plate 6o and compressing springs 6p, but when the bed reaches its uppermost position the groove in gear 6b coincides with that in sleeve 6f and the plate 75 6o, under pressure of springs 6p, moves the

locking bar into engagement with gear 6b overcoming the resistance of spring 6e. Preferably the cam member has two cam faces as 6j spaced 180 degrees apart and adapted to engage the adjacent ends of the lock bar simultaneously.

5 Cooperating with bed 2 is a cylinder 7 which is journaled in the side frames of the delivery section C of the press (Figs. 1 and 3) and lies opposite the upper end of bed 2 when the bed is in lowest position. Cylinder 7 has bearers 7a 10 coacting with bearers on bed 2, and on one of its journals is a gear 7b meshing with a rack 2b on bed 2. Suitable clutch means are provided whereby gear 7b is automatically locked to and unlocked from cylinder 7, to cause the cylinder to 15 rotate at a peripheral speed in unison with the travel of bed 2 during the printing stroke of said bed, and is stopped during the return non-printing stroke of bed 2.

In the construction shown gear 7c is locked to 20 and disengaged from its cylinder shaft by clutch means constructed and operating like those by which cylinder 6b is locked and unlocked from its shaft as above described, and therefore further detailed description of the clutch mechanism for cylinder 7 is unnecessary.

The bed 1 is supplied with ink from an inking mechanism mounted in section A below cylinder 6. The inking mechanism may be of any suitable construction. As shown it comprises a fountain 8, ductor 8a, a set of distributing rollers 8b, with proper adjusting and actuating mechanism, and two form rollers 8c. The particular inking mechanism used is not a feature of the present invention, and therefore further description 35 thereof is unnecessary.

The bed 2 is also supplied with ink from a similar inking mechanism mounted in section C of the press, including a fountain 9, ductor 9a, distributing rollers 9b, and two form rollers 9c. In 40 my press I am able to use two form rollers with resultant enhanced clearness and uniformity of impressions.

Rotatably mounted on shaft 4c is a feed cylinder 11 with which coat feed tapes 11a running over supporting rollers 11b and 11c mounted on shafts journaled in the side frames of section B. The tension of the tapes can be regulated by rollers 11d mounted in arms on a rock shaft 11e journaled in the side frames of section B, and having a crank arm engaged by a manually adjustable screw rod 11f.

55 In section C of the press adjacent cylinder 7 are mounted a pair of delivery cylinders 12 which deliver the sheets to a pile, or to a folding mechanism of any suitable construction. If desired the cutting blade can be removed or rendered inoperative, so that the cylinders deliver the web to a former folder (not shown), by which it is cut and folded in the usual manner.

60 It is sometimes desirable to re-wind the web after printing so that it may be subsequently re-fed to the folder together with a freshly printed web coming from the press in order to produce papers of larger size, or to enable the web to be re-printed in color before final discharge thereof. I have therefore provided a re-winding mechanism, in section C, which in the construction shown comprises a re-wind roll 13a journaled in the side frames of section C and having a pulley 70 13a driven by belt 13b from a pulley 13c on a shaft 13d journaled in section C. Shaft 13d has a gear 13e meshing with a compound gear and sprocket 14a on a shaft 14 journaled in section C. When re-winding said sprocket is driven 75

by a chain 14b from a sprocket 14c on the shaft of feed cylinder 11, whereby the web, when led to the re-wind roll, is re-wound as it is printed. The belt 13b can be suitably tensioned by an adjustable roller 13g mounted on a rock arm 13i adjustable by a manually operable screw 13j on the adjacent side frame of section C (see Fig. 1).

Suitable web guides are provided in the sections for directing the web from the roll to the feed cylinder and thence successively between the beds and cylinders to the delivery cylinders 12; or if desired to the re-wind mechanism. When the web is to be perfected and discharged to the folder, the lead is as follows:

15 The web *w* passes from roll W (see Figs. 1 and 4), to a guide *a* (in section A), thence around guide *b* (in section A), thence to and under guide *c* (in section B) and up past guide *d* to the feed cylinder 11, thence over guide *e* (in section 20 A) to and around a gravitational looping roller *f* guided in slots 15 in the side frames of section A; thence up over a guide *g* (in section A) down to and between the impression cylinder 6 and bed 1, where it receives its first impression. The 25 web passes from cylinder 6 up over guide *h* mounted on arms 16 on a rock shaft 16a (in section A) which shaft can be adjusted by a manually operable screw 16b in the usual manner. From guide *h* the web passes above the in-feed cylinder to a guide *i* (in section C), and 30 thence may pass down to cylinder 7, and between cylinder 7 and bed 2, by which it is perfected; or the web may be led from guide *i* to and under a roll 12a adjacent the upper cylinder 12, and 35 then to and between cylinder 7 and the bed, and thence to the delivery cylinders 12 (see Fig. 4). The tension on the web between the cylinders 6 and 7 is regulated by the gravitational looping roller *f*; and the register of the impressions is regulated by adjusting guide *h*. If it should be desired to deliver the web after it is printed on one 40 side by cylinder 6 and bed 1; the web could be led from guide *i* to and between roll 12a and upper cylinder 12, and then between cylinders 12 to the 45 folder.

When it is desired to re-wind the web the perfected web is led from cylinder 7 between it and roller 12a (as shown in dotted line *w*2 in Fig. 4), up to and over a guide *j* (in section C), then down 50 under a vertically movable looping roller *k* (guided in slots 17 in the side frame of section C); and thence up over a guide roller *l* to the re-wind roll on shaft 13.

If it is desired to re-wind the web before it 55 is perfected, it may be led direct from guide *i* to guide *j*, and thence under looper *k* up and over guide *l* to the re-wind roll.

When it is desired to assemble the re-wound web with a newly printed web the direction of rotation of roller *l* and the re-wind roll 13 is reversed (see Fig. 5), and the re-wound web is led back from roll 13 over roller *l* to and under looper *k* up over guide *j* down to and between roll 12a and upper cylinder 12, and is assembled with the 65 freshly printed web and delivered therewith by the cylinders 12 to the folder. To unwind the rewound web the direction of rotation of roll *l* can be reversed by any suitable means. In the construction shown a set of reversing gears 14s is provided to drive roll *l* during unwinding of the re-wound web and gears 14s may be driven from and by shaft 14, but when gears 14s are to be used, gear 14o is first disengaged from roller *l*, and vice versa, the pressman manually adjust-

ing the gears into or out of operative position or engagement.

If desired an electric or other suitable dryer (not shown) can be readily arranged in the press to dry the first impressions on the web before they reach the second impression cylinder.

The web is fed through the press by the co-operation of the cylinders with the forms on the moving beds aided by the in-feed roll 11 and the discharge cylinders 12. The gravity roller *f* 10 will ascend in the loop of web to compensate for the dwell necessary between the rotary in-feed and the intermittently acting cylinders. The first cylinder and bed advance the web to the second cylinder and bed, and the latter advance it 15 to the discharge cylinders 12, and the sheets to be severed equal in length the circumference of the printing cylinders. In the stop cylinder the circumference press of the cylinders determine the length of sheets to be severed; the cylinder 20 gaps providing for end margins of sheets. The impression cylinders are easily accessible for make ready and packing. Overlays can also be readily placed on either cylinder, which is another advantageous feature of my press.

The fountains and inking mechanisms are also easily accessible. The web does not have to pass around either fountain. The plurality of form rollers employed enhances the quality of the impressions. The quality of the product is also enhanced by the fact that the printed sides of the web (except when rewinding is used) does not pass over any guide or looping rollers. The gravitational looping roller *f* operates in a loop of the web between the in-feed and first impression cylinder, and not on a printed web; the only loop in the web when being perfected in blank paper.

The sections A, B, C, are separately completely assembled, as indicated in Fig. 10 so that they 40 can be more conveniently shipped to user than would be possible if their frames were integral. When they have reached their destination they are mounted upon a suitable base member D and securely fastened together to form a complete 45 unit. The sections A and C are shown as provided with inwardly extending side bars 20 and 22 which (when the sections are assembled with section B) are respectively fitted to planed surfaces on the adjacent sides of section B, and are 50 securely bolted thereto, as indicated in Figs. 1 and 3, so that the connected sections constitute a rigid frame; and when the sections are so united the mechanisms mounted in the respective sections will be properly operatively positioned relative to cooperating parts in the other sections.

The adjacent side frames of the sections A, B, and C virtually constitute an integral side frame, and they might be formed integral; but 60 that would render it necessary, in large presses, to ship the press mechanisms "knocked down" and then assemble all the parts in situ (as is now required in ordinary press construction), which greatly enhances the expense of press 65 erection. By making the press in sections as described, the several parts can be assembled in the sections at the factory, and the assembled sections shipped to the purchaser, and set up in situ by ordinary mechanics.

I claim:

1. In a web printing press; a pair of oppositely facing type beds; means for vertically reciprocating said beds; an impression cylinder adjacent and coacting with each bed; means for di-

- recting a web successively between the cylinders and beds, means for feeding the web, means for looping the unprinted web between the feed and first impression cylinder, and means for delivering the web after it passes the second bed and cylinder.
2. In a web printing press; a pair of outwardly and oppositely facing type beds; means for vertically reciprocating said beds; an impression cylinder adjacent each bed and coacting therewith; means for directing a web successively between the cylinders and beds, means for feeding the web, means for looping the unprinted web between the feed and first impression cylinder, means for delivering the web after it passes the second bed and cylinder, and an inking mechanism for each bed disposed at the outer side of the bed and below the coacting cylinder.
3. In a web printing press; a pair of oppositely facing type beds; means for vertically reciprocating said beds; an impression cylinder adjacent and coacting with each bed; means for directing a web successively between the cylinders and beds, means for feeding the web, means for looping the unprinted web between the feed and first impression cylinder, and means for delivering the web after it passes the second bed and cylinder; with a web re-winding mechanism adjacent the web delivery means, guides to direct the printed web to and from the re-wind roll, and means for looping the web between the re-wind roll and delivery.
4. In a web printing press; a pair of oppositely facing type beds, means for reciprocating said beds, an impression cylinder adjacent each bed and coacting therewith, the gaps in the cylinders being opposite the beds during the non-printing strokes of the beds, gearing between the beds and their respective cylinders; means for directing a web successively between the cylinders and beds, means for feeding the web, and means for delivering the web after it passes the second bed and cylinder.
5. In a web printing press; a pair of outwardly and oppositely facing type beds, means for reciprocating said beds, an impression stop-cylinder adjacent each bed and coacting therewith, the gaps in the cylinders being opposite the beds during the non-printing strokes of the beds, gearing between the beds and their respective cylinders; means for feeding the web, means for directing a web successively between the cylinders and beds, means for looping the unprinted web between the feed and first impression cylinder, and means for delivering the web after it passes the second bed and cylinder.
6. In a web printing press; a pair of oppositely facing type beds, means for reciprocating said beds, an impression cylinder adjacent each bed and coacting therewith, the gaps in the cylinders being opposite the beds during the non-printing strokes of the beds, gearing between the beds and their respective cylinders; means for directing a web successively between the cylinders and beds, means for feeding the web, and means for delivering the web after it passes the second bed and cylinder; with a web re-winding mechanism above the web delivery, guides to direct the printed web to the re-wind roll, and means for looping the web between the re-wind roll and delivery.
7. In a web perfecting press; a pair of type beds, an impression cylinder adjacent each bed and cooperating therewith, means for reciprocating the beds, means for counter-balancing the
- beds, a web in-feed mechanism, a web looping roller between said in-feed mechanism and the first bed and cylinder, and web delivery mechanism beyond the second bed and cylinder; with guides for directing a web from a supply to the in-feed mechanism, thence to the looper, then between the first bed and cylinder, then to the second bed and cylinder, and then to the delivery.
8. A web perfecting press comprising a pair of type beds, an impression cylinder adjacent each bed and cooperating therewith, means for vertically reciprocating the beds, means for counterbalancing each bed, a web in-feed mechanism above the beds, a web looping roller between said in-feed mechanism and the first bed and cylinder, and web delivery mechanism beyond the second bed and cylinder; with guides for directing a web from a supply to the in-feed mechanism, thence to the looper, then between the first bed and cylinder, then over the in-feed, then to the second bed and cylinder and then to the delivery; and an inking mechanism for each bed disposed below its coacting cylinder.
9. In a web perfecting press; a pair of type beds, an impression cylinder adjacent each bed and cooperating therewith, a shaft above the beds, crank wheels on said shaft, pitmans connecting the wheels with the beds, bed counterbalancing weights, means connecting the weights with their respective beds; a web in-feed, a web looping roller between the in-feed and the first bed and cylinder, and web delivery mechanism beyond the second bed and cylinder; with guides for directing web from a supply to the in-feed, thence to the looper, then between the first bed and cylinder, then to the second bed and cylinder, and then to the delivery; and inking mechanism for each bed.
10. In a web perfecting press; a pair of type beds, an impression cylinder adjacent each bed and cooperating therewith, means for vertically reciprocating the beds, bed-counter-balancing weights disposed between the beds, chains connecting the weights with their respective beds, and sprockets over which the chains are looped; a web in-feed mechanism above the beds, a web looping roller between said in-feed mechanism and the first bed and cylinder, and web delivery mechanism beyond the second bed and cylinder; with guides for directing web from a supply to the in-feed mechanism, thence to the looper, then between the first bed and cylinder, then over the in-feed, then to the second bed and cylinder, and then to the delivery.
11. In a web perfecting press; a pair of oppositely outwardly facing type beds, an impression cylinder adjacent the upper end and outer side of each bed and cooperating therewith, means for vertically reciprocating the beds, a web in-feed mechanism above the beds, a looping roller between said in-feed mechanism and the first bed and cylinder; and guides for directing a web from a supply up between the beds to the in-feed mechanism, thence to the looper, then between the first bed and cylinder, then over the in-feed, then to the second bed and cylinder, and thence to the delivery; with an inking mechanism for each bed disposed outside of the bed and below its coacting cylinder; a web re-winding roll above the delivery mechanism, and guides to direct the printed web to and from the re-wind roll.
12. In a web perfecting press; a pair of oppositely facing type beds, an impression cylinder adjacent the upper end of each bed and co-

- operating therewith, a shaft above the beds, crank wheels on said shaft, pitmans connecting the wheels with the beds; means for counterbalancing the beds comprising counterbalancing weights disposed between the beds, chains connecting the weights with their respective beds, and sprockets over which the chains are looped; a web in-feed mechanism above the beds, a looping roller between said in-feed mechanism and the first bed and cylinder, web delivery mechanism beyond the second bed and cylinder, guides for directing a web from a supply up between the beds to the in-feed mechanism, thence to the looper, then between the first bed and cylinder, then over the in-feed, and then to the second bed and cylinder, and thence to the delivery; and an inking mechanism for each bed disposed outside of the bed and below its coacting cylinder. 5
13. A sectional web perfecting press adapted to be assembled in the factory and shipped ready for erection in situ; comprising a main frame formed in three separable sections, the middle section containing opposite outwardly facing type beds, and web guides; one outer section containing an impression cylinder adapted to coact with the first type bed, and web guides; and the other outer section containing a cylinder adapted to coact with the second type bed, and web guides; the parts in the several sections when such sections are united being in operative relation. 10
14. A sectional web perfecting press adapted to be assembled in the factory and shipped ready for erection in situ; comprising a main frame formed in three separable sections, the middle section containing opposite outwardly facing type beds, and means for reciprocating the beds; one outer section containing an impression cylinder adapted to coact with the first type bed, and inking mechanism for said type bed; and the other outer section containing a cylinder adapted to coact with the second type bed, and inking mechanism for said second type bed. 15
15. A sectional web perfecting press adapted to be assembled in the factory and shipped ready for erection in situ; comprising a main frame formed in three separable sections, the middle section containing opposite outwardly facing type beds, means for reciprocating the beds, an in-feed, and web guides; one outer section containing an impression cylinder adapted to coact with the first type bed, inking mechanism for said type bed, and web guides; and the other outer section containing a cylinder adapted to coact with the second type bed, inking mechanism for said second type bed, and web guides. 20
16. A sectional web perfecting press adapted to be assembled in the factory and shipped ready for erection in situ; comprising a main frame formed in three separable sections, the middle section containing opposite outwardly facing type beds and web guides; one outer section containing an impression cylinder adapted to coact with the first type bed, inking mechanism for said second type bed and web guides; and the other outer section containing a cylinder adapted to coact with the second type bed, inking mechanism for said second type bed, and web guides; whereby when said sections are assembled and connected the web can be led to the in-feed mechanism, thence to and between the first bed and cylinder, then to and between the second bed and cylinder. 25
17. A sectional web perfecting press adapted to be assembled in the factory and shipped ready for erection in situ; comprising a main frame formed in three separable sections, the middle section containing opposite outwardly facing type beds and web guides; one outer section containing an impression cylinder adapted to coact with the first type bed, inking mechanism for said second type bed and web guides; and the other outer section containing a cylinder adapted to coact with the second type bed, inking mechanism for said second type bed, and web guides; said sections when connected enabling the web to be led from the supply to the in-feed mechanism, thence to the looper, then to and between first bed and cylinder, then over the in-feed to and between the second bed and cylinder, and then to the delivery. 30
18. In a web printing press; oppositely facing type beds, means for reciprocating said beds, an in-feed roll above the beds, an impression cylinder adjacent to and coacting with each bed, gearing between the cylinders and the in-feed roll; and clutch mechanism for locking the impression cylinders to the in-feed roll on the printing strokes of the beds and for disengaging them therefrom on the return strokes of the beds. 35
19. In a web printing press; a pair of oppositely facing type beds, an in-feed roll above the beds, crank wheels on the in-feed roll shaft, pitmans connecting said wheels with the beds to reciprocate the beds, an impression cylinder adjacent to and coacting with each bed, gearing between the cylinders and the in-feed roll shaft; and clutch mechanism for locking the impression cylinders to the in-feed roll shaft on the printing strokes of the beds, and for disengaging them therefrom on the return strokes of the beds. 40
20. In a web perfecting press; a pair of oppositely outwardly facing type beds, an impression cylinder adjacent the upper end and outer side of each bed and cooperating therewith, means for vertically reciprocating the beds, means for counterbalancing the beds, a web in-feed mechanism above the beds, a looping roller between said in-feed mechanism and the first bed and cylinder; and guides for directing a web from a supply up between the beds to the in-feed mechanism, thence to the looper, then between the first bed and cylinder, then over the in-feed, then to the second bed and cylinder, and thence to the delivery; with an inking mechanism for each bed disposed outside of the bed and below its coacting cylinder; a web rewinding roll above the delivery mechanism, and guides to direct the printed web to and from the re-wind roll, and a web looping roller between the re-wind roll and delivery. 45
21. In combination; an impression cylinder, a movable bed coacting therewith, a loose gear on the cylinder shaft meshing with a rack on the bed, a non-rotatable sleeve on the cylinder shaft adjacent the gear, a lock bar, a spring actuated rod connected with said bar and normally tending to disengage it from the gear, a movable cam member on said sleeve adapted to be intermittently oppositely rotatably shifted by interengaging pins on the cam member and gear, and a spring actuated plate engaging said cam member and adapted to overcome the rod actuating spring and cause the lock bar to engage the gear when permitted by the cam. 50
